United States Patent Office.

WILLIAM W. VIRDIN, OF BALTIMORE, MARYLAND.

Letters Patent No. 89,714, dated May 4, 1869.

IMPROVEMENT IN LOW-WATER INDICATORS.

The Schedule referred to in these Letters Patent and making part of the same.

To all whom it may concern:

Be it known that I, WILLIAM W. VIRDIN, of Baltimore, in the county of Baltimore, and in the State of Maryland, have invented certain new and useful Improvements in Self-Adjusting Low-Water Indicators; and do hereby declare that the following is a full, clear, and exact description thereof, reference being had to the accompanying drawing, making a part of this specification, in which—

Figure 1 is a vertical longitudinal section of the boiler and float, showing my apparatus in place, and

Figure 2 is a vertical central section of the valve, valve-seat, and flexible joint, by which the former are connected, by means of a pipe, with the outside of said boiler.

Letters of like name and kind refer to like parts in each of the figures.

My invention relates to a class of devices known as low-water indicators, having for their object the giving of an alarm when the water in a boiler reaches the lowest point that safety will permit; and

It consists in the employment and construction of a weighted float, so adjusted as to always rest upon and within the water, regardless of any foam that may arise, and which, through suitable mechanism, raises a valve, and permits the escape of steam from the boiler, so as to sound an alarm, when the water has fallen to a certain point.

It also consists in the employment and construction of a valve, secured to and operated by the action of the aforesaid float, said valve being slightly conical in shape, and fitting into a corresponding seat, and provided with suitable ports, which correspond with others in said seat, when said valve is raised by the action of said float, whereby steam is permitted to escape from said boiler, substantially as hereinafter described, and for the purpose set forth.

It also consists in the employment and construction of a wheel, provided with a series of radial arms, or floats, and pivoted within a suitable casing, through which the escaping steam is caused to pass and impart motion to said wheel, which, by means of a cam, or its equivalent, secured upon its axle, alternately raises and releases a hammer, which strikes upon a bell or gong, substantially as and for the purpose hereinafter described.

In the annexed drawing—

A represents the boiler, which may be constructed in any of the usual forms.

A float, B, constructed of sheet-metal, and hermetically sealed, is placed within said boiler, immediately above the flues, or the crown-sheet, where it rises or falls with the water between suitable vertical guides.

In order that said float may rest upon and within the water, so as not to be affected by foaming, it is weighted down by means of lead, b, placed within, until sufficiently immersed to effect the desired object.

The balance of the space within said float is filled with cork, or other light substance, for the purpose of keeping it distended.

Secured vertically within the centre of the float B is a hollow cup, or valve-seat, C, largest at the top, from whence it tapers slightly inward toward the bottom, and provided with a screw-cap, D, which is secured upon its top, so as to produce a steam-tight joint.

A valve, E, corresponding in outside shape to the interior of the valve-seat, rests therein, and is provided with a spindle, e, which projects downward through an opening in the bottom of said valve-seat, and has pivoted to its lower end a roller, e'.

The valve is somewhat less in height than the valve-seat, so as to allow of its being raised, and has one or more openings, e, passing through its walls, which openings, when said valve is thus raised, correspond with similar openings through the walls of the valve-seat, and permit steam to enter said valve.

Secured to the upper side of the cover D, by means of a flexible joint, F, of usual construction, is one end of a pipe, G, the opposite end of which is secured in a similar manner to a hollow plug, H, passing upward through and attached to the shell of the boiler.

An opening, d, made through the centre of the cap D, corresponds with a similar opening in the plug f, and, by means of the pipe G and plug H, affords communication between the interior of the valve E and the outside of the boiler, so that if said valve be raised when there is a pressure of steam within the boiler, a portion of such steam will escape through said valve, pipe, and plug, into the open air.

From the foregoing description, it will be readily seen that if suitable means are provided, whereby the valve E shall be raised, so as to permit the escape of steam, when the water in the boiler has reached the lowest point deemed safe, and if other means are provided, by which such escaping steam shall sound an alarm, one of the greatest sources of danger from the use of boilers will be removed, as none will be so foolhardy as to fail in giving prompt attention to the boiler when thus warned of the low stage of the water.

In order that the first-named object (the escape of steam) may be accomplished, it is only necessary that a suitable table, or stop, I, should be secured in a proper position beneath the float, so as to receive and arrest the stem of the valve, when the water and float have reached the desired level, while for sounding an alarm, a variety of means may be employed. I prefer, however, to cause a series of quick blows to be struck upon a bell or gong, so that from its dissimilarity to the ordinary sounds heard in or around an engine-room, or upon a steamer, more immediate attention may be secured.

To accomplish the latter object, I employ a wheel, K, provided with a series of radial arms, or floats, and pivoted within a suitable case, or box, L, which is se-

cured to one side, and forms part of a pipe, M, connected with the plug H, so that steam escaping through said pipe shall cause said wheel to rotate.

A bell or gong, N, is attached to the case L, and provided with a hammer, n, placed upon the end of a spring, against which a cam, k, secured to and revolving with the axle of the wheel K, is caused to strike at each revolution of said wheel, alternately raising and releasing said spring and hammer, and causing the latter to strike a quick succession of blows upon said bell, producing a sound similar to that of an alarm-clock.

For use upon a steamer, or within a large manufacturing, it may be desirable to have alarms placed in various places, so as to prevent the possibility of failure in securing immediate attention to the state of water in the boiler, for which purpose I place a branch-pipe, O, immediately above the wheel K, and from said branch-pipe extend pipes to the points desired.

When applied to the boilers of a steamer, one pipe should terminate in the pilot-house, and be open at its end, so that the escaping steam, however small the quantity, may warn the pilot, when sounds might be lost in the noise and confusion of a storm.

It may be found necessary to increase the weight of the valve, in order to enable it to withstand the pressure of the steam upon the stem. In such an event, a weight, e", applied to said stem, will produce the desired result.

Having thus fully set forth the nature and merits of my invention,

What I claim as new, and desire to secure by Letters Patent, is—

The weighted float B, when constructed and arranged substantially as herein shown.

Also, in combination with the weighted float B, the valve E, fitting into a corresponding seat, C, and operated by means of the spindle e, substantially as described and set forth.

Also, the construction and arrangement of the seat C and cover D, with reference to the valve E and joint F, substantially as herein shown and described.

Also, the within-described apparatus for indicating low water in a boiler, by the escape of steam therefrom, consisting of the weighted float B, valve E, provided with a suitable seat, C, and cover D, flexible joint F, pipe G, and plug H, all constructed and arranged substantially as herein shown and described, and, in combination therewith, the wheel K, pivoted within a suitable case, so as to be revolved by the escaping steam through the pipe M, and, by means of the cam k, secured to the axis of said wheel, alternately raise and release the hammer of a bell, as herein specified.

In testimony that I claim the foregoing, I have hereunto set my hand, this 17th day of March, 1869.

Witnesses: W. W. VIRDIN.
